UNITED STATES PATENT OFFICE.

VICTOR C. ARMSTRONG, OF HACKENSACK, NEW JERSEY, ASSIGNOR TO THE RAIL JOINT COMPANY, OF NEW YORK, N. Y., A CORPORATION OF NEW YORK.

LIGHTENED CONSTRUCTION FOR RAIL JOINTS.

Application filed July 10, 1925. Serial No. 42,795.

To all whom it may concern:

Be it known that I, VICTOR C. ARMSTRONG, citizen of the United States, residing at Hackensack, in the county of 5 Bergen and State of New Jersey, have invented certain new and useful Improvements in Lightened Constructions for Rail Joints, of which the following is a specification.

10 The present invention represents a carrying forward of the new principle of metal distribution for the Weber type of rail joint or equivalent structures wherein one of the joint members has a rail supporting base engaging the bottoms of the rails.

To that end the invention primarily has in view a novel application to the shoe of a Weber joint or equivalent structure of the principle of metal distribution disclosed in 20 the Armstrong and Groff Patent No. 1,484,487 granted January 8, 1924, wherein subnormal displacements of metal are advantageously located for the purpose of improving the "set" and "action" of the joint

25 while at the same time effecting an economical saving in the amount of metal used. In recent years one of the important problems of the railroad engineer, and the designer of rail joints has been to provide rail joints 30 of the highest efficiency from the standpoint of strength and adaptability to the loading and deflection stresses while at the same time avoiding the use of wasteful metal.

35 In studying those problems, and in observing the behavior of joints in track it has been found that the principle of subnormal metal distribution according to the invention of the Armstrong and Groff patent responds more nearly to the exacting requirements of the railroad engineers than former structures wherein stiffness and strength were obtained by additions or surplusage of metal in the forms of ribs or other reinforcement disposed in various ways.

40 This condition has applied to all forms of rail joints, and the present invention is intended to obtain novel and very useful results in a Weber type rail joint or equivalent structure by so locating the subnormal displacements of metal as to maintain the necessary strength and flexibility while at the same time cooperating with the filler block of the joint to hold the parts properly "set" when the bolts are tightened and also improving the "action" of the joint in adapt-

ing it to the rail wave motion, under passing loads; also providing a substantial reduction in the use of metal.

With these and other objects in view the invention consists in the features of improvement, in a novel relation, hereinafter more fully described, illustrated and claimed, and by way of example, certain practical forms of construction are shown in the drawings, in which:—

60 Figure 1 is a sectional view of a Weber type rail joint containing the present invention.

65 Figure 2 is a detail cross-sectional view on the line 2—2 of Fig. 1 showing the deformed part of the upright member of the shoe in its relation to the wooden filler block.

70 Figure 3 is a detail inside perspective view of a portion of the angle shoe of the Weber type rail joint showing one form in which the subnormal deformations may be made in the inner wall of the upright member of the shoe.

75 Figure 4 is a sectional view of the joint embodying a modification wherein the subnormal deformations in the shoe are continued into the upper face from the base plate of the shoe.

80 Like reference characters designate corresponding parts throughout the several figures of the drawings.

85 In adapting the improvements of the present invention to a Weber type of rail joint no departure is necessary from the general plan and organization of that type of joint. Accordingly, for illustrative purposes there is shown in Fig. 1 of the drawings a Weber type rail joint including in addition to the rail 1 the angle or splice bar 2 fitting the fishing spaces of the rail at one side of the joint, the channel bar 3 fitting the fishing spaces at the other side of the joint, the angle shoe 4 and the filler block 5 fitting in the channel 6 at the outer side of the channel bar 3 and having a flat outer face 7 clampingly engaged by the upright member of the shoe. The usual bolts 8 complete the joint.

100 The angle shoe 4 of the joint is shown to be of the conventional shape and type. It includes in its construction the upright member or bolting plate 8, the rail supporting base member or plate 9 underlying the rail bases and usually of a greater width than 110

the width of the rail bases and the reinforcing foot or toe 10 arranged at the outside of the shoe and at the juncture between the upright and base members 8 and 9 thereof. 5 According to the present invention it is proposed to improve the action of the shoe and at the same time materially lighten it by producing subnormal deformations 11 therein. These subnormal deformations are produced in the upright member or bolting plate of the shoe preferably in the final pass of the rolling mill, and while they may be of different shapes a preferred construction is to have said deformations in the form of 15 vertically extending depressions or cavities in the inner side of the upright member of the shoe. The standard or predetermined normal thickness of the upright member of the shoe is maintained at spaced intervals as at 20 12, leaving at such locations rib-like portions which serve to maintain the stiffness and strength of the shoe while also forming holding members which have an interlocking engagement with the filler block 4 when the 25 bolts are tightened. Between these locations 12 of normal wall thickness the depressions or cavities 11 produce wall portions 13 of subnormal thickness, and in the aggregate these subnormally thinned wall portions 30 13 represent a great saving in metal, as well as contributing to the flexibility of the joint. Another desirable and proven feature of this principle of metal distribution is that the same actually improves the 35 effective strength of the member in which the subnormal displacements are made and materially raises its elastic limit.

In the embodiment of the invention shown in Figures 1, 2 and 3 of the drawings the 40 vertical deformations 11 terminate short of the top edge of the upright as at 14 leaving a sealed joint 15 between the inner upper portion of said upright member 8 and the filler block 4 to exclude the elements of the 45 weather as well as dirt, and débris. Also, in the form of the invention referred to the deformations or cavities 11 do not extend to the bottom of the upright member of the angle shoe, but nevertheless have all the desirable attributes and functions referred to, 50 including that of the spaced normal thickness wall portions 12 having a biting engagement with the filler block 4.

The principle of the subnormal displacements of metal may be extended to include the base member 9 of the angle shoe as shown in Figure 4 of the drawings, and in such embodiment of the invention it may be preferable to have the depressions or cavities 11 in 55 the upright member of the shoe continued downwardly and uninterruptedly through and around the inside corner of the shoe as

at 16 and through and across the upper side of the base member of the shoe as at 17. Such extensive deformations repeated 60 throughout the length of the joint greatly improve the flexibility and action of the angle shoe while also effecting very substantial economies in the use of metal.

While the improvements herein described 65 have been shown as applicable to the Weber type of joint it will be understood that they are necessarily applicable to any chair type of rail joint having functions equivalent to the functions of the Weber joint. It will 70 also be understood that changes in the form, proportion and minor details of construction may be restored to without departing from the spirit or sacrificing any of the advantages of the invention.

I claim:

1. A lightened construction for rail joints including a shoe having a wall of standard thickness and subnormal displacements of metal therein.

2. A lightened construction for rail joints including a shoe having a member of standard wall thickness, said member having subnormal displacements of metal therein alternating with the standard wall thickness.

3. A lightened construction for rail joints including a filler block and an angle shoe, said angle shoe being provided in the inner side of its upright member with subnormal displacements of metal terminating short of the top edge of said upright member.

4. A lightened construction for rail joints including a filler block and an angle shoe, said angle shoe being provided at the inner side of its upright member with a plurality 100 of wall sections of subnormal thickness alternating with wall portions of predetermined normal thickness, said wall portions of predetermined normal thickness having a holding engagement with the filler block.

5. A lightened construction for rail joints including an angle shoe having in the inner side of its upright member and base plate subnormal thicknesses of metal in a plurality 110 of locations and alternating with wall portions of normal thickness.

6. A lightened construction for rail joints including an angle shoe provided at the inner side of its upright member and base plate with a plurality of cavities or depressions forming wall portions of subnormal thickness alternating with wall portions of normal thickness, said depressions or cavities extending through and around the inside corner of the shoe.

In testimony whereof I hereunto affix my signature.

VICTOR C. ARMSTRONG.
